Attorney

UNITED STATES PATENT OFFICE.

SYLVAN W. PACKER, OF KIRK, COLORADO.

DISK MOLDBOARD.

Application filed July 27, 1928. Serial No. 295,696.

The present invention relates to disk mold board designed for one, two, three and four row corn weeders and has for its prime object to provide a scraper with means for fastening the same so as to maintain the disk clean and prevent the dirt from getting into the boxes and wearing the bearings out.

Another very important object of the invention resides in the provision of a disk mold board of this nature that maintains the machine in good condition and enables the pull thereof to be lighter and generally enables the machine to accomplish the work in a better manner.

15 A still further very important object of the invention resides in the provision of a device of this nature which is simple in its construction, inexpensive to manufacture, strong and durable, thoroughly efficient and reliable in use, adjustable, and otherwise well adapted to the purpose for which it is designed.

With the above and other objects in view as will appear as the description proceeds, the invention resides in certain novel features 25 of construction, and in the combination and arrangement of parts as will be hereinafter more fully described and claimed.

In the drawing:

Figure 1 is a plan view of the mold board 30 attachment embodying the features of my invention,

Figure 2 is an edge elevation thereof, and

Figure 3 is a perspective view thereof indicating the manner in which the same may 35 be mounted.

Referring to the drawing in detail it will be seen that the numeral 5 denotes the scraper blade which is of rectangular formation having one longitudinal edge sharpened as indicated at 6.

An angular elongated shank 7 is riveted or otherwise securely attached to the blade intermediate the ends thereof as indicated at 8 so that a portion of the shank extends obliquely thereto. A bracket comprises an elongated body having a straight portion 9 merging into a curved portion 10 which in turn merges into a portion 11 oblique to the portion 9.

50 The portion 9 is provided with a longitudinally extending slot 12 and the shank 7 is provided with a similar slot 14. A bolt 15 passes through the slots 12 and 14 so that the shank may be held in different adjusted

position in angular relationship with respect to the bracket.

The extension or portion 11 is provided with an opening 16 so that the same may be anchored by one of the bolts on the bearing box. Obviously the shanks may be placed at any angle desired in respect to the bracket so that the scraper blade will engage the disk and maintain the same clean of dirt and the like and prevent this dirt from getting on to the journal boxes and making the pull 65 lighter and enabling the machine to do better work.

Obviously the attachment provides the necessary adjustment so that it may be engaged on one, two, three and four row corn weeders.

It is thought that the construction, utility and advantages of this invention will now be apparent to those skilled in this art without a more detailed description thereof.

The present embodiment of the invention 75 has been disclosed in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or 85 sacrificing any of its advantages.

Having thus described my invention, what I claim as new is:

The combination with a rotary disk of a farm implement having a bearing box therefor including a holding bolt, of a scraper for one face of the disk including a rectangular shaped blade having one longitudinal edge thereof sharpened, a shank including angularly related portions, one of which is secured to one face of the blade and the other portion extending angularly from the other longitudinal edge of the blade and having a longitudinally extending slot therein, a supporting bracket including a foot receiving the holding bolt of the bearing, and an angularly extending arcuate portion having a longitudinally extending slot therein, and a bolt passing through the slots of the bracket and shank, for holding the shank and blade in 195 a predetermined adjusted position.

In testimony whereof I affix my signature.

SYLVAN W. PACKER.
